DESIGN FOR A DRESS

Helen Smith von Baumann, New York, N. Y.

Application February 4, 1938, Serial No. 74,883

Term of patent 3½ years

To all whom it may concern:

Be it known that I, Helen Smith von Baumann, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the combination on the surplice dress disclosed of the specific, contrastingly colored gore inserted in the side of the skirt, said gore matching the sash and corsage in color, as shown.

I claim:

The ornamental design for a dress, substantially as shown and described.

HELEN SMITH VON BAUMANN.
